(57) **CLAIM**

The ornamental design for an upholstered bed, as shown and described.

DESCRIPTION

FIG. 1 is a rear, right, and top perspective view of an upholstered bed, showing my new design;
FIG. 2 is a front, left, and bottom perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof; and,
FIG. 8 is a bottom plan view thereof.
The broken lines in the drawings depict portions of the upholstered bed that form no part of the claimed design.
